UNITED STATES PATENT OFFICE.

ALBERT H. GLEASON, OF WABASH, INDIANA.

BUTTON-FASTENING MACHINE.

SPECIFICATION forming part of Letters Patent No. 375,149, dated December 20, 1887.

Application filed September 9, 1887. Serial No. 219,918. (No model.)

To all whom it may concern:

Be it known that I, ALBERT H. GLEASON, a citizen of the United States of America, residing at Wabash, in the county of Wabash and State of Indiana, have invented certain new and useful Improvements in Button-Fastening Machines, of which the following is a specification, reference being had therein to the accompanying drawings.

10 My invention relates to mechanism for securing eye-shank buttons to shoes and like articles by means of metallic fasteners which are clinched on the under side of the fabric.

The object of my invention is to produce a machine of this class which will feed a continuous wire through the eye of the button, cut off a length of wire on an angle, so as to give the staple pointed ends, bend the wire to form the staple, drive the staple downward through the fabric, simultaneously form a loop in the staple to receive the eye of the button and clinch the ends of the staple inward on the under surface of the fabric, and, finally, feed another button by a positive feed into position to receive the staple-forming wire.

25 The invention will first be described in connection with the accompanying drawings, and then clearly pointed out in the claims.

Figure 1 of the drawings is a front elevation 30 of my machine. Fig. 2 is a side elevation from the left of the machine, with button-feeding mechanism omitted, illustrating the mechanism for operating the plunger and the knife. Fig. 3 is a side elevation from the right 35 of the machine, on a smaller scale, showing the treadle mechanism and the tension device. Fig. 4 is a detail front view showing the manner of adjusting the treadle. Fig. 5 is a broken front elevation of the machine enlarged, showing 40 the loop forming and clinching dies, the manner of hinging them to the plunger, and the parts with which they coact. Fig. 6 is a vertical section taken on the line xx , Fig. 5, showing the loop forming and clinching dies elevated 45 and a button in position on the bending-block. Fig. 7 is a like vertical section showing the dies depressed, with the first button down on the anvil and another button in position on the bending-block. Fig. 8 is a broken front

50 elevation of the machine with the button-spring in position and the guide-plates removed. Fig. 9 is a like view of the machine with the guide-plates attached. Fig. 10 is a perspective view of the guide-plates from the front. Fig. 11 is a perspective view of said 55 plates from the rear. Fig. 12 is a horizontal section taken on the line yy of Fig. 10, showing, also, the position of the knife when severing the wire. Fig. 13 is a perspective view of a portion of the knife. Fig. 14 is a broken 60 rear elevation of the machine, illustrating the button-feeding mechanism, with one button (in dotted lines) resting on the bending-block and another button ready to be forced down into said block by the feed-finger attached to 65 the plunger. Fig. 15 is a horizontal section taken on the line zz , Fig. 14, showing the button-trough. Fig. 16 is a detail perspective view of the bending-block and bending-die, with a 70 button and wire on the block, the wire, when bent to form the staple, being shown in dotted lines. Fig. 17 is a perspective view of the cap-plate. Fig. 18 is a detail perspective view showing the loop forming and clinching dies as they are about to act on the staple. 75 Fig. 19 is a detail front view of said dies in the act of forming the loop and clinching the staple.

Referring to the drawings, A represents the treadle-frame, from which rises a hollow standard, B, to the top of which is secured the table C. To the top of the table, in line with standard B, is secured a short hollow flanged standard, B', to a lug, b', on the flange of which is attached an anvil, D, and at the top of standard B', formed integral therewith, is a right-angularly bent bracket, B'', to which certain parts of the machine, hereinafter mentioned, are secured.

E represents a reciprocating rod, which plays 80 through standard B' and the table and in the upper end of standard B. To its lower end is secured a smaller rod, E', which is also secured to the treadle F, which is hinged to one leg of the treadle-frame, its front end working in and 85 steadied by a slotted guide, A', through the top and bottom of which pass set-screws a a', for purposes hereinafter mentioned. The 90

said rod E' is encircled for a portion of its length by a coil-spring, E², the lower end of which is secured to the rod, while its upper end bears against a plate, e, seated in an annular recess, b, in standard B.

The reciprocating rod E carries at its upper end an arm, G, which curves upwardly and is bent at a right angle to the axis of the rod, as seen in Figs. 1 and 2. To the horizontal portion of this arm is attached the plunger H, (see Figs. 1, 2, and 14,) which is beveled on its edges and works between correspondingly-beveled guideways I secured to the horizontal portion of bracket B², (see Figs. 2, 3, 6, and 14,) the upper ends of said ways being secured to a cross-bar, i, on the rear side, as seen in dotted lines in Fig. 1 and full lines in Fig. 2.

J J represent the loop forming and clinching dies. The upper end of each of these dies is rounded, as at 1, and fits loosely in a correspondingly-shaped recess in the front side of plunger H at its lower end, so as to be free to swing therein, being held in place in the plunger by a face-plate, 2, secured to the plunger by a screw, 3, as seen in Figs. 6 and 7. At the lower end, on the inner side, these dies are each recessed, so as to form jaws 4, between which the wire is clamped to form the loop for receiving the shank of the button, and below the jaws they are shouldered, as at 5, so as to press on top of the staple on each side of its loop to drive it through the fabric and clinch the points, all as seen in Fig. 19. The jaws and shoulders are grooved on the inner edges, as at 6, Fig. 6, so as to prevent the staple slipping out of position. A spring, j, keeps the dies normally apart.

In Figs. 10, 11, and 12 I have shown the guides for the dies, the button-shank, and the wire; in Fig. 8, a front view of portions of the machine with these guides detached; and in Fig. 9 a like view with the guides in position, but with the cap-plate, hereinafter described, omitted. These guides K K' consist each of two front plates, k k', and two rear plates, k² k³. Plate k is perforated at 7 for the passage of the staple-forming wire w, and it is also beveled on its under side from its inner edge, as at 8, in order to admit the beveled front end of the knife Q, so as to cut the wire on a slant. Plate k' is recessed on its inner edge, as at 9, (see Fig. 9,) to receive the free end of the wire, the recess being elongated in order to allow the end of the wire to describe an arc of a circle, as it must necessarily do while being bent to form the staple. Both plates k and k' have inwardly-sloping shoulders 10 at their lower ends for forcing the dies J J together, and thus forming the loop in the staple, as seen in Fig. 19, the lower ends of said dies being rounded on the outer sides, so as to ride freely over the shoulders. Plates k² and k³ are substantially alike, except that the former is cut out at 11 for the passage of the cutting end of the knife. They are attached to the rear side of the front

plates, k k', between which the dies J J are guided, and overlap the inner sides of the front plates, leaving just sufficient space between for the passage of the shank of the button. The upper ends of the overhanging portions of the rear plates are curved rearwardly, so as to lie in the path of the button-feeding mechanism and take the button as it is fed forward, as seen in Figs. 9, 10, and 11.

I, Fig. 17, represents the cap-plate above alluded to, which is attached to the ways I I over the guides K K'. This plate will be fully described in connection with the bending-die and bending-block.

M represents the bending-block, on which the wire is bent to form the staple. It is formed integral with a slide, M', of the form shown in Fig. 16, which works on a ledge, 12, on the cap-plate, and is held in place on said ledge by a spring, 13, secured to one of the ways I.

N represents the bending-die, comprising two horizontal legs, n, adapted to straddle the bending-block, and a vertical arm, n'. This arm is slotted, as at 14, and its upper end is curved forward, as clearly seen in Figs. 6, 7, and 16. The legs of this die work in and are guided by guideways 15, and the slotted arm n fits over a cam projection, 16, on the cap-plate. Legs 17, formed integral with guideways 15, prevent the bending-block slide from tipping while the block is being moved out of the way of the clinching-dies, as hereinafter explained. The legs of the die are notched on the under side near their outer ends, as at 18, for the purpose of preventing the wire from slipping while being bent. To a pin, 19, on the bending-die is attached one end of a coil-spring, 20, inclosed in a casing, 21, attached to one of the ways I.

O and O' are two friction-rolls for feeding the wire to form the staples, the wire being taken from a reel, 22, mounted in a casing, 23. Roll O is provided with ratchet-teeth, with which a pawl, 24, pivoted to a cam, 25, engages, the pawl being steadied by a guard, 26, rigidly attached to the cam. The cam is pivoted to one of the guideways I in such position as to lie normally in the path of a finger, 27, adjustably secured to the plunger, as seen in Fig. 1. By the adjustability of this finger all lost motion occasioned by wear of the ratchet may be avoided.

In order to regulate the tension of the feed-rolls on the wire, the lower roll, O', is journaled in a right-angular bar, 28, to which is rigidly fixed a vertical arm, 29, that slides up and down in a two-arm support, s, attached to bracket B², said arm having an internally-screw-threaded lug, 30, which is located between the arms 31 and 32 of the support s. The upper arm, 31, extends outward considerably beyond arm 32, and is perforated for the free passage of a screw-threaded bolt, 33, which screws into the threaded lug 30, and a coil-spring, 34, encircles the bolt between its

head and the top of arm 31. It follows that by this construction the lower roll presses the wire between it and the upper roll by spring-pressure, and that this pressure can be readily and accurately adjusted by simply turning the bolt.

Q represents the knife, the forward end of which is beveled outwardly, as seen in several of the views, so as to work close into guide K 10 and cut the wire on a slant, and its forward end is also beveled rearwardly on the under side, as clearly shown in Fig. 13, so as to give a shear cut. The knife is provided with an operating-arm, Q', pivoted to bracket B², and 15 oscillated to operate the knife by a cam, R, having a flange, r, through a slot in which it is adjustably secured to arm G. Being thus adjustable, as the contact-surfaces of the cam are worn by the knife-arm the cam can be 20 raised or lowered, so as to make the knife cut sooner or later, as required.

The mechanism I have devised for feeding the buttons into the machine singly by positive motions is very simple, as will be seen on reference to Figs. 14 and 15, wherein S represents a trough of a width at the top to permit the buttons to rest and slide on its edges, as clearly shown in Fig. 15. One side of the trough at its lower end is cut away, as at 35, for a purpose presently to be explained. The trough is secured in an inclined position by any suitable means to the rear side of one of the guideways I, with its lower end resting directly over the curved upper ends of the rear plates, 35 k² k³, of guides K K', and in front of a button-holding spring, T, the upper end of which is secured to one end of a horizontal bar, t, secured to the rear side of one of the guideways I. In the trough there is a wire, w', on which 40 the buttons are strung, its lower end terminating directly over the space between the guide-plates k² k³, so that as the side of the trough is cut away at 35 a button, on reaching the end of the wire, will drop with its shank 45 in the opening between the said plates k² k³, when it will be in position to be driven home onto the bending-block on the descent of the plunger by means of a feed-finger, U, attached to the rear side thereof, as seen in full lines in 50 Figs. 6 and 7 and in dotted lines in Fig. 14. The wire w' is held in place in trough S by a double-flanged button, w², fitting in a notch in the closed upper end of the trough. A toothed wheel, W, grooved on its periphery, is attached to the guideway I directly under the trough and in such position that its teeth will pass into it through a slot, 36, in its under side. The wheel is revolved by means of a 55 gravity-pawl, V, attached through a slot to the way J, one end of said pawl engaging the teeth of the wheel and its other end being engaged by the feed-finger in its upward movement to draw the pawl up, and thus turn the wheel the distance of one tooth. As the 60 wheel revolves, its teeth engage the shanks of the buttons, and thus feed the buttons down

the trough and in front of the button-spring T and between the guide-plates k² k³ one at a time.

By the adjustability of the treadle I have 70 attained two valuable results—that is to say, by the lower set-screws I am enabled to limit the descent of the plunger and its attached dies to suit any thickness of fabric, and by the upper set-screws I can so regulate the upward movement of the reciprocating rod as to 75 avoid all concussion in the upper portion of the machine.

The operation of my machine is as follows: Assuming there is a button in position on the 80 bending-block, a downward pressure on the treadle will pull down the reciprocating rod E, with its attached arm G, that carries the plunger H and cam R, and as the finger 27, attached to the plunger, bears down on the cam 85 25 the latter is swung on its pivot far enough around to clear the path of the finger, which causes pawl 24 to turn roll O, and by friction roll O', the space of one tooth, and thereby feed the wire through the eye of the button. 90 The downward movement of cam R will rock the knife arm, and thus cause the knife to sever the wire, by which time the loop forming and clinching dies J J will have reached the legs n n of the bending-die N. Then as 95 dies J J continue to descend they will force the bending-die down onto the wire over the bending-block M (the notches 18 in the legs of said die engaging the wire to hold it steady) and continue forcing it downward until the 100 wire has been bent down the sides of the block, as seen in dotted lines in Fig. 16, by which time the outwardly-curved upper end of arm n' of the bending-die will have reached the cam projection 16 on the cap-plate L, which will cause 105 the bending-die to swing outward, carrying with it, against the stress of spring 13, the slide M', on which the bending-block is formed, as seen in Fig. 7, which is prevented from tipping during this movement by the lugs 17 on 110 the cap-plate. It will be observed that the bending-block is thus moved forward just out of the path of the dies J J, and in order to avoid the necessity of moving it any farther forward I groove it on its rear side, as at 38, 115 for the passage of the button-shank, as seen in Figs. 6 and 7, there being also a groove, 39, in the top of the block for the reception of the shank while the staple is being formed. As 120 the block recedes, the ends of the staple come into contact with two studs, 40, at the rear of ledge 12 on the cap-plate L, and the staple is thereby stripped from the block. Further downward movement of the loop forming and clinching dies J J carries the button and staple 125 down onto the fabric f on anvil D, and as the points of the staple enter the fabric the rounded ends of the dies J J come in contact with the shoulders 10, formed on the guide-plates k k', which cause said dies in their descent to be 130 forced together, whereby the jaws 4 4 clamp the wire on each side of the button shank be-

tween them, and thus form the loop. By this time the points of the staple have passed through the fabric and are in concavities *d* in the top of the anvil, and are clinched inward 5 by the shoulders *5* on the dies bearing on the top of the staple. The button being now secured, the dies *J J* begin their upward movement, and when their lower ends have passed the bending-block the latter is forced back 10 into its normal position by spring *13* and the bending-die is carried upward by the coil-spring *20*. As plunger *H* moves upward it carries with it the attached feed-finger *U*, upon the end of which is formed a small hook, *u*, 15 which catches under the curved end of the gravity-pawl *V*, thereby raising it the length of its slot, which is sufficient to turn the button-feeding wheel another tooth, which forces the next button off the end of wire *s* and in front 20 of the button-spring *T*, in position to be forced down onto the bending-block on the return of the feed-finger.

Having thus described the construction and operation of my machine, what I claim as new, 25 and desire to secure by Letters Patent, is—

1. In a button-fastening machine, substantially as described, the combination, with a guide for the button, rolls for feeding a wire through the eye of the button, a knife for severing the wire, a bending-block over which the wire is bent to form a staple, and an anvil, of a wire-bending die and a pair of loop forming and clinching dies, the latter adapted to form a loop in the staple for the shank of the 30 button and to clinch the staple on the under side of the fabric.

2. The combination, with a guide for the button, rolls for feeding a wire through the eye of the button, a knife for severing the wire, a bending-block over which the wire is bent to form a staple, and an anvil, of a wire-bending die, a plunger, ways for guiding the plunger, and a pair of loop forming and clinching dies attached to the plunger, adapted to form a 35 loop for the shank of the button and to clinch the staple on the under surface of the fabric, all arranged to operate substantially as described.

3. In a button-fastening machine constructed 40 as described, a pair of loop forming and clinching dies hinged at their upper ends to the plunger and formed at their lower ends with jaws for forming the loop in the staple and shoulders for pressing upon the staple to clinch it, suitable means for pressing the dies toward 45 each other on their descent, and a spring between them for pressing them apart on their ascent, all combined in the manner set forth.

4. In a button-fastening machine constructed 50 as described, the slide carrying the bending-block, the ledge on which the slide rests, a spring bearing against the slide, the bending-die having a vertically-slotted and outwardly-curved arm, a cam projection over which said 55 arm is placed, and a spring for elevating the bending-die, whereby said die and the bend-

ing-block are caused to clear the path of the loop forming and clinching dies on their descent and to assume their normal positions on the upward movement of said dies, the whole 70 combined in the manner set forth.

5. In a button-fastening machine constructed as described, the slide carrying the bending-block, the ledge on which the slide rests, provided at its rear with studs for stripping the 75 staple from the block as the latter moves forward, a spring bearing against the slide, the bending-die having a vertically-slotted and outwardly-curved arm, a cam projection over which said arm is placed, and a spring for elevating the bending-die, the whole 80 combined and operating in the manner described.

6. In a button-fastening machine, substantially as described, the combination, with the wire-feeding rolls, a cam pivoted above said 85 rolls, and a pawl pivoted to said cam and engaging with ratchet-teeth on one of the rolls and the plunger, of a finger secured to the plunger and engaging with the cam in such manner as to swing it out of its path, and 90 thereby cause the pawl to turn the feed-rolls.

7. In a button-fastening machine, substantially as described, the combination, with the wire-feeding rolls, a cam pivoted above said 95 rolls, and a pawl pivoted to said cam and engaging with ratchet-teeth on one of the rolls and the plunger, of a finger adjustably secured to the plunger and engaging with the cam, whereby lost motion in the ratchet mechanism may be taken up.

8. In a button-fastening machine, the combination, with the wire-feeding rolls, of a wire-guiding plate having a slanting perforation for the passage of the wire and beveled off at its inner rear edge, as shown, a knife 105 whose front end is beveled outwardly to correspond with the bevel on said guide-plate and rearwardly on the under side in order to make a shear cut, and suitable mechanism for operating the knife, substantially as described.

9. In a button-fastening machine, substantially as described, the combination, with the reciprocating rod and the arm attached thereto, of the knife and its operating-arm pivoted to a stationary part of the machine, and a cam 115 attached to the arm on the reciprocating rod with which the knife-arm engages, whereby in the reciprocations of the rod the knife is operated to sever the staple-forming wire.

10. In a button-fastening machine, substantially as described, the combination, with the reciprocating rod and the arm attached thereto, of the knife and its operating-arm pivoted to a stationary part of the machine, and a cam 120 adjustably secured to the arm on the reciprocating rod with which the knife-arm engages, whereby the knife may be made to cut sooner or later, as required.

11. The combination, with the button-guiding plates and a spring in rear of said plates 125 for holding the button in position, of an inclined trough leading to said guides, having a

slot in its under side and provided with a longitudinal wire on which the buttons are strung, a toothed wheel journaled below said trough, its teeth passing through the slot in the trough 5 and engaging with the shanks of the buttons on the wire, suitable mechanism for rotating said wheel, the plunger, and a feed-finger attached to the plunger, whereby the buttons are first fed positively, one at a time, to the

button-guides, and are then forced down to the 10 bending-block.

In testimony whereof I affix my signature in presence of two witnesses.

ALBERT H. GLEASON.

Witnesses:

ALBERT SPEIDEN,
G. W. BALLOCH.
